CLAIM

The ornamental design for a load carrying cart body, as shown and described.

DESCRIPTION

FIG. 1 is a perspective view of a load carrying cart body showing my new design.

FIG. 2 is a side elevational view thereof.

FIG. 3 is a rear elevational view thereof.

FIG. 4 is a top plan view thereof.

FIG. 5 is a front elevational view thereof.

FIG. 6 is a front elevational view thereof in its collapsed condition.

FIG. 7 is a perspective view of a load carrying cart body showing a second embodiment.

FIG. 8 is a side elevational view of FIG. 7.

The broken lines shown in FIGS. 1 through 8 are for illustrative purposes only and form no part of the claimed design.

The fragmentary criss-cross pattern shown in FIGS. 1, 4, 6 and 7 is understood to be continuous throughout the area shown.
